UNITED STATES PATENT OFFICE.

GEORGE H. ROBERTS, OF PROVIDENCE, RHODE ISLAND, ASSIGNOR TO FREEMAN-DAUGHADAY CO., OF CHARTLEY, MASSACHUSETTS, A CORPORATION OF MASSACHUSETTS, ALSO DOING BUSINESS AS PROVIDENCE COLLAR BUTTON COMPANY, OF PROVIDENCE, RHODE ISLAND.

DESIGN FOR A STATUETTE.

Application filed September 17, 1923. Serial No. 7,227. Term of patent 3½ years.

To all whom it may concern:

Be it known that I, GEORGE H. ROBERTS, a citizen of the United States, residing in the city and county of Providence, and State of Rhode Island, have invented a new, original, and ornamental Design for a Statuette, of which the following is a specification, reference being had to the accompanying drawing, forming a part thereof.

The figure is a perspective view of a statuette, illustrating my new design.

I claim:

The ornamental design for a statuette, as shown.

GEORGE H. ROBERTS.
